**SOLDER CLEANING TOOL FOR REMOVING
SOLDER FROM THE APERTURES OF
PRINTED CIRCUIT BOARDS**

Joseph A. Sylvester, Wayne, N.J., assignor to
Hexacon Electric Company

Filed Feb. 22, 1972, Ser. No. 228,425

Term of patent 14 years

Int. Cl. D8—05

U.S. Cl. D8—14

FIG. 1

FIG. 2

FIG. 3

FIG. 4

FIG. 5

FIG. 6

FIG. 1 is a perspective view of a solder cleaning tool for removing solder from the apertures of printed circuit boards showing my new design, taken from the lower rear.

FIG. 2 is a plan view thereof which is a mirror image of the bottom view.

FIG. 3 is a rear view thereof.

FIG. 4 is a right side view thereof which is a mirror image of a view from the left side.

FIG. 5 is a perspective view thereof taken from the upper right.

FIG. 6 is a front view thereof.

I claim:

The ornamental design for a solder cleaning tool for removing solder from the apertures of printed circuit boards, as shown and described.
